UNITED STATES PATENT OFFICE.

CHARLES PHELPS, OF OSKALOOSA, IOWA.

SECTIONAL BOILER-FURNACE.

1,242,856.

Specification of Letters Patent.

Patented Oct. 9, 1917.

Application filed March 16, 1915. Serial No. 14,664.

To all whom it may concern:

Be it known that I, CHARLES PHELPS, a citizen of the United States, and resident of Oskaloosa, in the county of Mahaska and State of Iowa, have invented a certain new and useful Sectional Boiler-Furnace, of which the following is a specification.

The objects of my invention are to provide a sectional boiler furnace in which the sections are made comparatively small and light, so that they may be easily handled and shipped, and also in this connection to provide furnace sections each of which is complete in itself so that no matter how many of these sections are employed in a single furnace, the completed furnace will at all times retain the same general proportion of essential furnace elements, that is to say, the proportions between the grate area, the fire area, the air circulating system and the water circulating system will remain the same and unchanged.

A further object is to provide a furnace of this class especially adapted for use in burning soft or bituminous coal in such a manner as to obtain a maximum efficiency from the coal and also to consume the black smoke and soot. In this connection it is my object to provide a furnace in which a relatively large amount of coal may be placed at one time which will be gradually and slowly burned off from the bottom and sides in such a manner that the heat from the burning mass of coal will come in direct contact with a relatively large fire surface so that the maximum efficiency of the coal will be utilized, and further in this connection it is my object to provide a furnace of this class in which sufficient air may freely circulate through the grate and upwardly around the sides of the mass of coal to produce perfect combustion even with a relatively large mass of coal on the grate proper.

A further object is to provide a furnace of this class in which the water circulating system is so arranged as to avoid counter currents or churning within the furnace sections, whereby a constant water level is maintained and "dry" steam is produced in the super heater device at the top of each section.

A further object is to provide a furnace of this class in which all of the necessary pipe fittings, both for water and smoke, may first be permanently secured to the rear section and then any required number of sec-

tions may be applied to the rear section and to each other without the necessity of ever changing or moving the rear section or the pipe fittings connected to it, so that the furnace may be enlarged or reduced in size at will very quickly and easily and without expensive labor, and when so altered in size the furnace will be complete in itself with the proper amount of ash pit capacity, grate surface, fire surface, air circulating system and water circulating system as required to produce and provide a maximum efficiency for fuel consumption and a maximum efficiency for heating water and producing "dry" steam.

My invention consists in the construction, arrangement and combination of the various parts of the furnace whereby the objects contemplated are attained as hereinafter more fully set forth, pointed out in my claims and illustrated in the accompanying drawings, in which:

Figure 1 shows a front elevation of a furnace embodying my invention, with part of one of the filling plates broken away to show the adjacent furnace section.

Fig. 2 shows an end view of the furnace embodying my invention, with the front removed. In this figure a quantity of fuel is shown, and there are arrows illustrating the paths of the air circulation upwardly around the sides of the fuel and then downwardly toward the flue openings.

Fig. 3 shows an enlarged, detail, sectional view on the line 3—3 of Fig. 2.

Fig. 4 shows an edge view of a number of furnace sections coupled together, showing the inside faces thereof, taken from a vertical line through the center of the furnace.

Fig. 5 shows a rear elevation of my improved furnace showing the flue pipes and water circulating pipes connected therewith.

Referring to the accompanying drawings, it will be noted that the furnace is composed of independent sections extending transversely across the furnace, and also that each section is formed of two complete half sections divided along a vertical, central, longitudinal line through the furnace. Each of these half sections is in itself a complete unit, and any half section of the furnace except the front and back ones, may be readily and easily removed and a new one substituted.

Each section comprises a hollow body portion consisting of a top member 10, an inner

upright water chamber 11, an outer upright water chamber 12, a series of water circulating members 13 extending upwardly and outwardly from the inner water chamber 11 to the outer water chamber 12, and a bottom water chamber 14 extending upwardly and outwardly from the water chamber 11 to the water chamber 12. Below the hollow water chamber is an upright leg 15 to support the furnace section in an elevated position and to form part of the ash pit which is indicated by the numeral 16. Along the outer and top edges of each section is a flat rib 17 projecting beyond the sides of the furnace section, and so arranged that these ribs 17 of two adjacent boiler sections will engage each other and form a closure or outer furnace wall. The inner upright water chamber of each section is tapered at 18, as shown in Fig. 3, so that the spaces between two of these chambers near the fire box are greater than the spaces between them at a point spaced apart from the fire box, thus providing air circulating chambers 19 between the adjacent portions 18.

In order to provide for proper combustion of the fuel in the furnace, I have provided on each furnace section a series of draft guiding wings 20, 21 and 22. These wings are formed on the side faces of the inner upright water chambers 11, and the lower one 20 extends from a point adjacent to the top of the grate surface upwardly and outwardly, and then upwardly along the outer edge of the part 11. At this point there is formed a draft passageway 23 between the wings 20 and 21, and another draft passageway 24 is provided between the wings 21 and 22. These wings on the adjacent sections contact with each other when the sections are placed together, so that a passageway for the products of combustion is provided between the fuel on the grates and the wings 20, 21 and 22, so that even if the combustion chamber is comparatively full of coal, as illustrated in Figs. 2 and 3, the products of combustion may pass freely in an upright direction from a point near the grate between the body of fuel on the grate and the wings 20, 21 and 22. The advantages of the openings 23 and 24 will be set forth more fully hereinafter.

Between the inclined hollow section 13 and the hollow top 10 is a draft opening 25 into which the products of combustion may pass from the fire box. From this point the products of combustion may either flow longitudinally of the furnace or they may pass downwardly between the parts 13 to the circular draft passageway 26, at which point they will be conducted rearwardly toward the rear section and the flue attached thereto.

Assuming that there is some black smoke arising from the coal, and also that along the sides of the body of coal there is a flame, then the black smoke in its passage from the

passageway 25 to the flue 26 will travel downwardly between the hollow section members 13. In so doing they will be brought into contact with flames passing through the openings 23 and 24. The flames will pass through these openings before going upwardly, because there is a shorter passageway through these openings 23 and 24 to the flue, hence this black smoke will be brought into contact with these jets of flame passing through the said openings 23 and 24 and the black smoke will be consumed. On the inner face of each furnace section is a grate rest member 27, and a grate section 28 is mounted therein. The grate proper forms no part of my present invention, and hence these grate sections will not be specifically described.

In order to connect the furnace sections together, I have provided at the top of each section a series of lugs 29. Extended upwardly on the outer surfaces of the furnace sections is a series of lugs 29 extended outwardly, and on the legs 15 below the hollow section are the lugs 30, and near the central portions of the furnace sections are the upwardly extending lugs 31. All of these lugs are connected together by means of short bolts 32 extending only from one lug to the other in the manner illustrated at the bottom of Fig. 4, so that any section may be removed by first removing the bolts connected to it.

At the rear of the rear section the air circulating openings are sealed up by means of the detachable plates 33, and the flue 34 is connected to these plates in line with the flue openings 26, and this flue 34 is connected to a flue riser 35.

The front section is also provided with plates 36 to close the air circulating openings, and it is provided with the usual fuel door 37, draft door 38, and ash pit door 39.

The water connections for the furnace sections are arranged as follows: At the upper outer corner of each section is a water circulating opening 40. At the lower inner corner of each section is a water circulating opening 41. Above the body of the furnace section at the inner corner of each section is a hollow upright steam dome 42 to communicate with the interior of the hollow section and provided with steam circulating openings 43.

In connecting together two side by side furnace sections, tapered push nipples of ordinary construction, not shown, are provided to connect these various water and steam circulating openings together so that the water and steam may flow through these openings from one furnace section to the other. These various push nipples are firmly seated in place when the furnace is erected by drawing the said bolts 32 up tight. The only pipe fittings which need

be applied to the completed furnace is a header 44 to connect together the water circulating openings 44 at the rear section, and a cold water supply pipe 45 is connected 5 with this header at the top of the rear section. The steam circulating openings 43 are connected together by means of the header pipe 46 leading to a riser 47.

Some of the advantages of my improved 10 furnace are as follows:

By having the furnace built up of half sections, as shown, and by having each half section provided with a grate supporting member, a surface to contact with the fire, 15 a draft circulating system, a water circulating system, a steam dome and an ash pit member, it is obvious that no matter how many sections are employed in one furnace, the furnace will work at maximum efficiency 20 because there is the same proportion of grate surface, fire surface, air circulating system, water circulating system, steam dome, and ash pit, and these proportions are not changed by adding or taking away 25 some of the sections.

Another advantage is that by having the completed furnace provided with a grate and with upright water columns forming the sides of the fire box, and so arranged 30 as to confine the fuel, and also so arranged that draft may pass up along the sides of the body of fuel and between these hollow boiler sections, a very large quantity of fuel may be placed on the grate within the fire 35 box and this fuel may be burned without producing black smoke on account of these free draft passages up along the sides of the body of fuel.

Another advantage is that by having the 40 sections so arranged that the draft will pass first upwardly through the fire box and then outwardly and downwardly to the flue, and by having the parts so arranged that jets of flame direct from the fire box may come in 45 contact with the products of combustion just before entering the flue, any volatile gases or smoke will be ignited by said jets of flame and be consumed before entering the flue.

Another advantage is that by having all 50 of the various sections communicate with each other freely so that water may pass from one to the other both at the top and bottom, and by having the boiler sections 55 extended below the grate surface, and by having the parts of the sections that communicate between the inner upright column and the outer upright column inclined upwardly and outwardly, I avoid all possibility 60 of creating counter currents and churning of the water within the boiler sections to thereby maintain a steady water line at the top of the boiler sections. The short black arrows in Fig. 2 show the water 65 circulation within the sections. The great-

est amount of heat is, of course, supplied to the inner upright columns, and so the water will rise in these columns. The coldest place will, of course, be the outer upright columns, and the water will flow 70 downwardly in the outer upright columns. The communicating hollow water chambers are inclined upwardly and outwardly because the upwardly flowing current in the inner upright columns tends to expand, and 75 will flow upwardly and outwardly to the outer upright columns and then join the downwardly flowing currents therein and descend to the lowest point of the section which is below the grate. That is to say, 80 the furnace section, so far as the water circulation is concerned, is arranged to conduct the currents of water along the paths they would ordinarily take, for instance, in a tank when great heat was applied to the 85 interior thereof. However, by means of the construction of my improved sections, I avoid all possibility of counter currents and the water moves rapidly and freely throughout these sections, thus giving the furnace 90 a maximum efficiency for creating steam or heating the water. The advantage of a steady water line is that the steam dome may be placed close to the top surface of the water line and may therefore be cast 95 integral with the furnace section, and at the same time "dry" steam may be taken off from the steam dome.

A further advantage is that by having each section a complete furnace unit, pipe 100 fittings need only be applied to the rear section and after that the assembling of the other sections can be quickly and easily accomplished by unskilled workmen, thus resulting in a great saving of time in the 105 erection or repair of the furnace.

I claim as my invention:

1. In a furnace of the class described, the combination of a number of sections formed hollow for water circulation, each being 110 provided with upright hollow water columns to form the sides of the fire box, said columns being so shaped at a point above the grate as to provide for the circulation of gases and air between them in an upward direction around the sides of the body of fuel resting on the grate and against the inner edges of said upright columns, and draft ribs on the front and rear surfaces of the sections near the outer edges of the 115 inner upright columns shaped to deflect the gases and products of combustion arising from the fuel chamber upwardly to a point near the top of the fuel chamber, said draft ribs being provided with small openings 120 whereby jets of flame from the fire may discharge outwardly.

2. In a furnace, the combination of a series of furnace sections formed hollow for water circulation, each furnace section being pro- 130

vided on its front and rear faces around its outside edge, with a rib to coact with the ribs of corresponding sections to seal the exterior of the furnace, said furnace sections being also provided with inner upright water columns to form the sides of the fire box, and being also provided with a hollow top section, hollow outer upright columns, and a series of connecting hollow members 10 inclined upwardly and outwardly from the inner upright columns to the outer ones, there being near the bottom of each section a draft passageway, the water chambers of the sections being spaced apart to permit the circulation of the products of combustion from the fuel chamber outwardly to said

outer rim, and the inner upright columns being provided on their front and rear faces above the grate line with draft ribs arranged to deflect the gases and products of combustion from the fire box upwardly between the sides of the inner upright columns to a point near the top of the fuel chamber, said draft ribs being provided with small openings whereby jets of flame from the fire 25 may discharge outwardly.

Des Moines, Iowa, February 25, 1915.

CHARLES PHELPS.
